UNITED STATES PATENT OFFICE.

THOMAS J. KIERNAN, OF COLUMBIA, SOUTH CAROLINA, ASSIGNOR TO BROOKS IMPROVED STEAM VALVE COMPANY, OF COLUMBIA, SOUTH CAROLINA, A CORPORATION OF SOUTH CAROLINA.

STEAM-VALVE.

SPECIFICATION forming part of Letters Patent No. 734,885, dated July 28, 1903.

Application filed December 30, 1902. Serial No. 137,192. (No model.)

To all whom it may concern:

Be it known that I, THOMAS J. KIERNAN, a citizen of the United States, residing at Columbia, in the county of Richland and State 5 of South Carolina, have invented certain new and useful Improvements in Steam-Valves; and I do hereby declare the following to be a full, clear, and exact description of the invention, such as will enable others skilled in 10 the art to which it appertains to make and use the same.

My invention relates to improvements in steam-valves; and it consists of certain novel features that will be hereinafter described 15 and claimed.

Reference is had to the accompanying drawings, in which the same parts are indicated by the same letters throughout both views.

Figure 1 is a longitudinal vertical section 20 in the plane of the axis of the cylinder and shows the valve and interior of the steam-chest. Fig. 2 shows a section along the line 2 2 of Fig. 1 and looking in the direction of the arrows.

25 A represents a cylinder, and B a steam-chest, inclosing the valve N, mounted on the shaft K. This valve-shaft is preferably squared where it engages the valve, or it may be keyed or rigidly attached to the valve in 30 any convenient way. The valve N is substantially cylindrical in form and rocks between curved bearings m on the valve-seat M and q on the balance-plate Q. The steam-port a opens into the passage m⁰ in the valve-seat, and the port a' opens into the corresponding passage m'. a² is the exhaust-port, which connects with the exhaust-passage n³ in the valve and also with the curved exhaust-chamber n², cut into the valve.

35 The valve is provided with steam-passages n and n' and is also cut away, as at n⁴ and n⁵, to permit the passage of live steam to the cylinder when the valve is in the proper position, as indicated by the arrows in Fig. 1. 40 On top of the valve is the balance-plate Q, which plate moves in a guideway in the block P, and the said block is held in place by means of bolts R. The top of the balance-plate carries four strips S, forming a square,

two of which strips are shown in Fig. 1. 50 Steam enough is kept on the back of the balance-plate between these strips to keep said plate adjusted.

From the inspection of Fig. 1 it will be seen that if the valve be rocked to the left, as 55 shown in that figure, live steam will enter through the passages n and n' into the passage m⁰ and thence through the port a into the cylinder, while exhaust-steam will pass through the passages m', n², and n³ into the 60 exhaust-port a². If the valve be rocked to the opposite direction, the cycle of flow of steam will be reversed.

It will be obvious that the ports a and a' 65 may be placed at any desired position relative to the ends of the cylinder. It will be seen that the steam is supplied through both the top and bottom of the valve at the same time, and by this arrangement the valve may be made to operate after being rocked through 70 a very short distance, thus insuring a quick feed and a quick exhaust of the steam. The double exhaust-passages in the valve are a feature of special importance. The valve is intended especially for use for locomotives 75 and where it is difficult to secure a quick enough exhaust. By duplicating exhaust-passages in the valve, as shown, a far more rapid flow of exhaust-steam is secured. This is especially desirable for all high-speed engines and for use with pistons having a short 80 stroke.

Various other advantages of the herein-described valve and mechanism will suggest 85 themselves to any one skilled in the art.

Having thus described my invention, what I claim, and desire to secure by Letters Patent of the United States, is—

1. The combination with a cylinder provided with steam and exhaust ports and a 90 curved valve-seat, of a substantially cylindrical valve rocking on said valve-seat, steam-passages in the side of said valve, and double exhaust-passages in the base of said valve, substantially as described. 95

2. The combination with a cylinder provided with steam and exhaust ports and a curved valve-seat, of a substantially cylind-

drical valve rocking on said valve-seat, steam-passages in the side of said valve, and a curved exhaust - passage, and an exhaust - chamber with a rib separating the two in the base of said valve, substantially as described.

3. The combination with a cylinder provided with steam and exhaust passages and a curved valve-seat, of a substantially cylindrical valve mounted transverse to the cylinder and rocking on said valve-seat, with steam-passages in the side of said valve and two exhaust - passages in the base of said valve, substantially as described.

4. The combination with a cylinder provided with steam and exhaust ports and a curved valve-seat, of a substantially cylindrical valve mounted transverse to the cylinder and rocking on said valve-seat, with double steam-passages in each side, and double exhaust-passages in the base of said valve, substantially as described.

5. The combination with a cylinder provided with steam and exhaust ports and a curved valve-seat, of a substantially cylindrical valve mounted transverse to the cylinder and rocking on said valve-seat, with steam-passages in the side of said valve par-

allel to the axis thereof and extending through the valve-body, double exhaust-passages in the base of said valve, with a curved balance-plate bearing on the top of said valve, and a guide-block mounted in the steam-chest and holding said friction-plate in place, substantially as described.

6. The combination with a cylinder provided with steam and exhaust ports and a curved valve-seat, of a substantially cylindrical valve mounted transverse to the cylinder and rocking on said valve-seat, with double steam-passages in the side of said valve parallel to the axis thereof, a curved exhaust - passage and an exhaust-chamber in the base of said valve, with a curved friction-plate bearing on the top of said valve, and a guide-block mounted in the steam-chest and holding said friction-plate in place, substantially as described.

In testimony whereof I affix my signature in presence of two witnesses.

THOMAS J. KIERNAN.
